UNITED STATES PATENT OFFICE

2,244,429

AMALGAMATOR AND CONCENTRATOR

Clarence D. Overton, Los Angeles, Calif.

Application April 29, 1940, Serial No. 332,133

3 Claims. (Cl. 209—191)

The present invention relates generally to a method and apparatus for recovering metallic gold from gold bearing ore, and more particularly to the amalgamation and concentration of free gold, with the object, among others, of accomplishing the same in a manner which will effectively do away with all danger of the flowering of the mercury and waste thereof as well as of free gold.

It is well known in the practical art that anything in the way of methods, machines or apparatus for the above purpose, permitting or tending toward separation of the mercury into small particles, or flowering of the mercury as it is called, develops considerable loss in both mercury and gold. In small particles, the gold and mercury may find their way into, and outflow with, the dross or tailings. It is one of the primary purposes of the present invention to eliminate this loss by the provision of a method and apparatus tending to keep the mercury together and prevent separation thereof, as well as insure intimate contact therewith, of every particle of free gold in the ore handled.

A further object of the invention is the provision of a method and apparatus according to which every portion or particle of the ore treated is forced to pass through a body of mercury at a time when both ore and mercury are similarly and powerfully acted upon to bring about their intimate churning or grinding together.

A further object of the invention is the maintenance of a body of mercury in a manner definitely presenting an axial or central area substantially removed from the perimeter of the body, and the feeding of ore, containing free gold, into the said axial or central area of the maintained body of mercury and thereafter confined, during forceful intermixing of the ore and mercury, against movement out of the mercury except in a direction radially of the mercury body from its said central area to its perimeter, and in this way carry on thorough, efficient amalgamation in a manner which is novel both as to the method as well as to the apparatus.

A still further object is the provision of an apparatus of the above character which may be made in various sizes having different capacities and which will be equally efficient in all such sizes.

A still further object of the invention is the provision of an apparatus in which successful amalgamation and concentration may be carried out with minimum power requirements, and with slow grinding of the ore and mercury in a more

or less frictionless contact with the mixing, churning or grinding parts or elements.

While appreciating that my invention is readily adaptable to numerous modifications and changes, I will now describe the best mode so far devised by me for its practical success, the description in detail referring to the accompanying drawing, illustrating the invention and forming a part of this specification. In the drawing,

Figure 1 is a side elevation of the apparatus of this invention.

Figure 2 is a top plan view thereof with the upper gears removed.

Figure 3 is a vertical, sectional view taken centrally therethrough on the line 3—3 of Figure 1.

Figure 4 is a vertical, sectional view taken centrally therethrough along a line at right angles to the section of Figure 3, and,

Figure 5 is a horizontal sectional view taken substantially on line 5—5 of Figure 1.

Referring now to the above figures of the drawing, I preferably utilize an upwardly opening, vertically cylindrical casing 10 within and upon the base of which there is disposed a stationary or bottom grinding plate 11. This plate as plainly seen extends across the full diameter of the casing base and is to be formed of a hard, wear-resisting material for a reason which will presently appear.

The upper face of the bottom plate 11 forms a horizontal flat surface on which a plurality of hard steel grinding balls 12 are disposed, preferably in number to substantially cover the surface and at the same time allow somewhat free movement of the balls for independent rotation on constantly varying axes under the effect of an upper grinding plate 13 overlying, and resting of its own weight evenly upon, the grinding balls 12.

The upper grinding plate 13 is of substantially reduced diameter with respect to the lower plate, and is supported in coaxial relation to the latter upon the lower end of its axially upstanding shaft 14, so that an annular, upwardly opening channel 15 is thus formed between the perimeter of the upper grinding plate 13 and the casing wall. This channel, it will be noted, forms and affords the only communication from the space between the plates 11 and 13 into the casing 10 above the plate 13.

The shaft 14 is hollow and forms a feed tube downwardly through which the ore from the mill is constantly fed from the lower end of the tube into the axial or central area of the space

between the grinding plates 11 and 13, since the lower end of the feed tube opens downwardly through the upper plate 13 and, as plainly seen in Figures 3 and 4, extends below the plate 13 which it supports, in order to prevent crowding of the balls 12 below the feed tube where material is fed to the space between the plates 11 and 13. Obviously the ore so fed into the space between the plates 11 and 13 is intimately intermixed with the mercury, maintained at a substantial level above the bottom plate 11.

The above action in the present apparatus means more than mere mixing of the ore and mercury. The freely revolving and rotating balls, which form an anti-friction support for the upper plate 13, actually grind the ore and mercury together slowly and thoroughly without danger of either getting away from the other as long as they are in the space between the plates. In the course of the above action, the ore is of course prevented from movement out of the mercury in any direction except radially from the center to the perimeter of the plates 11 and 13, and it is along this path that the mixture slowly finds its way to the outer annular channel 15 where it moves upwardly into the casing above the upper plate 13.

It is plain that in the above operation every particle of free gold will be brought into intimate contact with the mercury with which it amalgamates. Thus as the mixture rises through the channel 15 around plate 13 the heavier amalgam will separate from the dross or tailings, the former passing upwardly along the inner surface of the wall of casing 10 for discharge through a side outlet or concentrate take-off 16. The tailings, being somewhat lighter, rise upwardly along the upper conical cover 17 of plate 13 to finally discharge through a discharge nipple 18 in communication with a tailings discharge pipe 19, said nipple having its inner receiving end opening within the casing adjacent to the upper inner end of the cone 17.

The casing 10 may have laterally outstanding flanges 20 at diametrically opposite points of its upper open end. To these flanges may be bolted the end portions of a cross bar or bridge 21. This bridge has an opening through which the hollow feed shaft 14 rises, and forms a support for an upstanding bearing cage or cylinder 22 around shaft 14. In the cylinder 22 are upper and lower bearings 23 and 24, in contact with the shaft 14 at vertically spaced points of the latter.

Above the bearing cylinder 22, the shaft 14 is shown with a fixed gear 25 which may be of the bevel type to engage a similar gear 26 of reduced size, on a drive shaft 27 extending from, and actuated by, any suitable source of power. However other types of gearing may be used, since the present apparatus lends itself to efficient operation with small power requirements.

The bridge 21 also serves as a support for rigid pendant stirring arms 28 in series at opposite sides of the shaft 14, with their lower ends terminating near the surface of the cone 17 at several points thereof, so as to prevent the tailings from building up on the cone surface and in this manner insuring ready discharge of said tailings through the discharge pipe 19.

In order to maintain uniform feed of ore into the space between the grinding plates as previously mentioned, I preferably utilize, within the feed shaft 14, means which, in connection with

this rotating shaft, will control such feed and at the same time prevent clogging thereof.

For the above purpose I may employ a stationary, twisted or spiral feed strip or ribbon 29 within the feed shaft 14, which strip or ribbon may be secured in any suitable manner as by anchoring the lower end of the same to the bottom plate 11. Any other suitable means may, however be used for this purpose, either stationary or movable of itself.

It is believed that, from the foregoing description, the advantages in operation of the present apparatus will be readily recognized. Every particle of free gold is forced into intimate contact with the mercury in an area in which ore and mercury are intermingled during slow rotation of the upper grinding disc or plate, and rotation and roaming of the grinding balls 12, well adapted to efficient functioning with low power demands and without danger of loss of free gold or through flowering of the mercury.

The apparatus of this invention is economical in its manufacture as well as its use, and is not only capable of a long effective life, but is singularly free of parts likely to need frequent repair or replenishment, and is a fitting complement to the method it so well carries to effective conclusion.

Having thus fully described my invention, what I claim and desire to secure by Letters Patent is,

1. In combination, a casing, means forming a mercury space horizontally within the lower portion of the casing including superimposed plates of which the upper plate is rotatable, with its perimeter spaced from the wall of the casing to form a mixture discharge channel opening upwardly into the casing, balls freely disposed in said mercury space and upon which the upper plate rests, a hollow upright feed shaft rotating said upper plate and opening downwardly therethrough into the center of the mercury space, an inverted cone atop the rotating upper plate having a wide lower end on said plate and having a narrow upper end closely surrounding the shaft at a point spaced vertically above the rotating plate, said casing having a concentrate take-off through its wall above the upper plate, and a tailings discharge member extending radially inwardly through the upper portion of the wall of the casing and having its inner receiving end opening within the casing adjacent to the upper end of the cone where it surrounds the shaft.

2. In combination, a casing, means forming a mercury space horizontally within the lower portion of the casing including superimposed plates of which the upper plate is rotatable with its perimeter spaced from the wall of the casing to form a circumferential mixture discharge channel opening upwardly into the casing, balls freely disposed in said mercury space and upon which the rotatable plate rests, and a hollow upright feed shaft rotating said upper plate and opening downwardly therethrough with its lower end extending below the upper plate and projecting into the center of the mercury space to prevent the balls from crowding in the lower discharge end of the said feed shaft.

3. In combination, a casing, means forming a mercury space horizontally within the lower portion of the casing including superimposed plates of which the upper plate is rotatable, with its perimeter spaced from the wall of the casing to form a mixture discharge channel opening upwardly into the casing, balls freely disposed in

said mercury space and upon which the upper plate rests, a hollow upright feed shaft rotating said upper plate and opening downwardly therethrough into the center of the mercury space, a cone atop the rotating upper plate and around the shaft, said casing having a concentrate take-off through its wall above the upper plate, a tailings discharge member extending through the upper portion of the wall of the casing and having its inner receiving end opening within the 10

casing adjacent to the upper end of the cone, a bridge member across the casing and having a bearing support around the shaft, bearings in said support engaging the shaft at vertically spaced points, and stirring arms depending from said bridge member and having their lower free ends terminating adjacent to the surface of said cone at spaced points along the sloping surface of the latter.

CLARENCE D. OVERTON.
